OF JERSEY CITY, NEW JERSEY, A CORPORATION OF NEW JERSEY.

SPOOL-WINDING MACHINE.

1,132,739.

Specification of Letters Patent. Patented Mar. 23, 1915.

Application filed September 5, 1906. Serial No. 833,883.

To all whom it may concern:

Be it known that I, CAMPBELL SCOTT, a citizen of the United States, residing at Yonkers, in the county of Westchester and State of New York, have invented a new and useful Improvement in Spool-Winding Machines, of which the following is a specification.

My invention relates to winding machines, and one of its objects is the provision of automatic means for indicating a defect or irregularity in the material to be wound.

A further object of the present invention is to provide means for stopping a spool-winding machine when a defective portion of the material to be wound appears or if such material is broken while being wound.

Another object of the invention is the provision of automatic means for stopping a spool-winding machine for insulated wire when such wire is insufficiently insulated or bare at any portion thereof, and such portion reaches a predetermined point.

Another object is to provide automatic means for stopping a spool-winding machine when a part of the material about to be wound is not of uniform diameter as when it is knotted, and such part reaches a predetermined point.

A further object of the invention is to provide improved and simplified means for guiding wire, thread or the like, and a retarding device to effect a semi-automatic winding.

Other objects of my invention will appear hereinafter, the novel combinations of elements being pointed out in the claims.

In the accompanying drawings, Figure 1 represents more or less diagrammatically a spool-winding machine with my invention applied thereto, parts being shown in section; Fig. 2 is a side elevational view of a detail of the semi-automatic guiding mechanism; and Fig. 3 is an elevational view of a type of foot-operated electric switch that may be used for controlling the motor.

Heretofore it has been found difficult to wind spools of insulated wire free from bared portions or knots by reason principally of the neglect of the attendant to watch closely the wire as it is being wound.

It is one of the principal objects of the invention to obviate these difficulties by providing automatic means for stopping the apparatus until the irregularity in the mate-

rial to be wound can be repaired. Furthermore, if the wire breaks, the winding mechanism will immediately stop and prevent the material that has already been wound from becoming loosened. It will also be seen hereinafter that the guiding mechanism is semi-automatic in its action so as not to require the constant attention of a person skilled in winding the insulated wire in even compact layers.

Any suitable type of motor may be used and operated mechanically or electrically. In this instance, I have shown an electric motor M mounted on the bed plate B. A standard 4 supports the bearing 5 through which passes the motor shaft S. This shaft is screw-threaded at its outer portion 3 on which is adapted to turn the nut 10. A cone 9 is secured to the shaft S at the right of the bearing 5, as viewed in Fig. 1, and on the outer end of the shaft is mounted an additional cone 9' so as to have longitudinal but no circumferential movement with respect to the shaft S. The spool 11 on which the insulated wire or other material is to be wound, is placed between the cones 9, 9' and the nut 10 is then turned to connect said spool 11 rigidly to the shaft S so as to turn therewith.

16 designates an electro-magnetic brake apparatus that may be used and comprises a brake shoe 17 cooperating with the brake pulley 151. Between the brake shoe 17 and the magnet frame 35 is connected the brake spring 18. The brake shoe 17 is connected to move with the core 19 which is adapted to play in the solenoid 29 while a rod 21 connects said core with the movable contacts of the main line switch 22.

The spool or drum 150 from which the insulated wire is to be drawn is secured between the cones 13, 13' on an auxiliary shaft in a similar manner to the mounting of the spool 11 or other devices on which the wire is to be wound. This auxiliary shaft is mounted in the bearings 6, 6' and carries between the latter a friction pulley 25 of a brake-retarding device. This brake is constantly applied and is here shown as comprising a lever 30 having a fixed pivot 32 and carrying a brake shoe 29 at an intermediate point. A spring 34 between the adjusting nut 33 and the toe 31, and encircling the pivoted rod 36, effects the application of the brake shoe 29 to the pulley 25.

with sufficient friction to prevent the wire from becoming slack while being wound and to insure its being wound tightly on the spool 11.

- 5 1 designates a coupling to connect sections of the shaft S. In this instance the wire 12 appears to pass from the reel 150 under this coupling and thence in engagement with the direction pulleys 7 and 8 between which is located a circuit-closing device 55. This circuit-closing device comprises a fixed conductor 42 with an arc-shaped face with which the insulated wire has a sliding engagement. Opposite the conductor 42 and 15 also in engagement with the wire 12 is a lever 41 pivoted at 40. A spring 43 acts on the outer end of this lever tending to force the same against the conductor 42. If desired, anti-friction rollers 44 and 44' may be 20 mounted on the lever 41 and conductor 42, respectively, in such positions that the wire 12 when passing between said lever and conductor will engage for the most part with the said rollers. The conductor 42 and lever 41 should be made of good conducting material and so also rollers 44 and 44', so that when a bared portion of the insulated wire passes between said rollers, the fixed conductor 42 and lever 41 will be electrically 25 connected with each other. Preferably the direction pulleys or rollers 7 and 8 are so located that a slight bend of the insulated wire takes place between the rollers 44 and 44' to assist in laying the wire bare if the 30 insulation is not sufficient.

From the roller 8 the wire 12 extends around the fixed direction sheave 15 and thence to the guiding arm 47 through an opening 51 at the outer end of which it passes 35 directly to the spool 11. Above the pivotal point of the arm 47 the wire 12 passes through a guideway 53 formed by the semi-circular upward projections 52 and 52'. To prevent the wire from leaving this guideway a cap 56 may be placed over the projections 52 and 52' as shown in Fig. 2.

The arm 47 is pivoted at 57 to have a vertical movement, and the outer end of the arm is pressed into contact with the layers on 40 the spool 11 by the spring 48. The outer end of the arm may be lifted from the spool by means of the handle 46. The lever 47 is also mounted to have a horizontal movement which may be effected by actuating the handle 46. The arm 47 with its pivotal bearings 49 may be mounted on the bracket 54, which in this instance, is shown fixed on the bed plate B.

Pivoted at 63 to the lever of the handle 46 45 is a piston rod 62 which is also connected to the piston 64 moving in the cylinder 65 of a dash-pot. This dash-pot is preferably filled with fluid, as oil, and a by-pass 68 provided for the passage of the fluid from one 50 side of the piston to the other through the

ports 66 and 66'. To vary the rate of flow of the fluid through the by-pass, a valve 67 may be provided and connected to a pointer 69 adjacent a scale 70.

Now, upon the operation of the winding 70 mechanism, the wire 12 will be drawn onto the spool 11 while the arm 47 is being guided manually by means of the handle 46. It will be seen that by reason of the dash-pot, this handle cannot be given sudden movements. By varying the opening in the valve 67, a certain manual force applied to the lever 46 will tend to effect a winding of the wire 12 on the spool 11 in even compact layers. It should be particularly noted, however, that by reason of the spring 48, the outer end of the arm 47 is pressed against the wire on the spool 11. If the arm 47 were held stationary the wire would, of course, ride up on a previous spiral. By giving the 80 arm 47 a certain retardation by means of the dashpot, the engagement of the wire 12 with a previous spiral may be depended upon to automatically move the arm 47 laterally and thus secure an automatic winding of the 85 wire 12 on the spool 11. For instance, if the wire is being wound on the spool 11 as shown in Fig. 1, the wire 12 as it reaches the spool 11 is continually being brought into contact with the wire that has just been 90 placed on the spool during the preceding rotation, so that the arm 47 is forced to the left, the retardation due to the dashpot being 95 adjusted to insure compact winding.

When the main line switch 96 is closed, a 100 circuit may be traced from the + main through wires 97, 98, and 58, switch 14, wire 59, foot switch 37, wire 60, brake magnet solenoid 20, wires 61, 71, 102, and 103 to the - main. The brake shoe 17 will thereupon 105 be lifted from the brake pulley 151 and the main line switch 22 closed. A circuit may now be traced from the positive main through the contacts 119, 118, wire 107, to the brush 108 of the motor M, and thence 110 through the shunt winding 111 of the motor and through the armature to the brush 110, wire 112, contacts 106, 105, wires 102 and 103 to the negative main. The motor will now 115 start to operate the winding mechanism. For the sake of simplicity I have shown no refinement of motor-controlling apparatus other than the brake apparatus 16 and the main line switch 22 for controlling the ordinary operation of the motor.

It will be observed that the switch 14 and 120 37 are connected in the brake magnet circuit. Therefore, upon pressing the lever 39 with the foot against the action of the spring 38, the switch 37 may be opened which will 125 effect the application of the brake, the opening of the main line switch, and the consequent stopping of the motor and the winding mechanism connected thereto.

23 designates an electro-magnet connected 130

to the switch 14. To the upper end of the core of this magnet is connected a device for holding the switch 14 in closed or in open position. This device is here shown as comprising a stem 24 connected to the core of the magnet and also to a lever 27, the outer end of which engages with a friction spring having a lateral bend 28. When the switch is open, the outer end of the lever 27 resting on this spring bend prevents the switch from being closed again until it is manually operated by means of the handle 26 connected to the stem 24. When the magnet 23 is energized to automatically stop the motor and winding mechanism, the holding device is depended upon to prevent the motor from immediately starting up again. The advantage of this holding device will be apparent when it is noted that if a bared portion of the wire 12 electrically connects the lever 41 and conductor 42, a circuit will be closed only a short time from the positive main through solenoid 50 by way of wires 97, 98, 72, 51, lever 41, roller 44, wire 12, roller 44', and wires 71, 102, 103, to the negative main. Upon the energization of the magnet 23, the switch 14 is opened and held open until the wire is repaired, and then the switch 14 may again be closed manually by means of the handle 26 to effect the starting of the motor and the operation of the winding mechanism. If the wire breaks it is evident that the spring 43 would immediately force the rollers 44 and 44' into engagement with each other and therefore the magnet 23 would be energized to open the switch 14 to effect the stopping of the motor.

It should be noted that the lever 41 has an extension 74 at the outer end of which is a set screw 75 adjacent a conducting spring 73, electrically connected to the fixed conductor 42. Now, if a knotted portion of the wire 12 should pass between the rollers 44 and 44', the lever 41 will be forced laterally from its normal position and the end of the set screw 75 brought into engagement with the spring 73. A circuit will thereupon be closed through the solenoid 50 by way of the lever 41, extension 74, set screw 75, and spring 73 to the conductor 42, instead of directly through the rollers 44 and 44' as when a bared portion of the insulated wire appears. When such knotted portion of the wire or a portion thereof of greater than a predetermined diameter passes between the conductor 42 and lever 41, the electro-magnet 23 is energized and the switch 14 opened to effect the stopping of the motor and winding mechanism until such irregularity can be repaired. It will therefore be seen that whether the irregularity in the insulated wire consists of a breaking thereof, or of a portion becoming insufficiently insulated, or of non-uniform diameter, the switch 14 will in each case be opened and the

motor and winding mechanism stopped until such irregularity can be repaired.

Obviously those skilled in the art may make various changes in the details and arrangement of parts without departing from the spirit and scope of my invention, and I desire, therefore, not to be limited to the precise construction herein disclosed.

What I claim is:—

1. In a winding machine, the combination with a shaft, of means carried by said shaft for receiving the material to be wound, a motor for rotating said shaft and receiving means, an auxiliary shaft, a reel mounted on said auxiliary shaft and carrying the material to be wound on said receiving means, retarding mechanism associated with said auxiliary shaft to maintain the material taut while being wound, means for controlling said motor, and a device operated by irregularities in the material to be wound to effect a stopping of the motor. 75

2. The combination with winding mechanism, of an electric motor for driving the same, brake apparatus comprising a magnet, a main line switch operated by said magnet, an auxiliary switch in circuit with said magnet, an electro-magnet associated with said auxiliary switch, and a circuit-closer operated by an irregularity in the material to be wound to effect the energization of said last-named electro-magnet and the opening of said auxiliary switch. 90

3. The combination with winding mechanism for insulated wire, of a motor for driving the same, motor-controlling means, an electro-magnetic switch associated with said motor-controlling means, a plurality of relatively movable conductors normally held apart by the insulated wire but electrically connected by an uninsulated portion thereof to effect the operation of said electro-magnetic switch and the stopping of the motor, and a circuit-closer co-acting with said conductors and operated by a portion of enlarged diameter of said insulated wire to effect the same operation of the switch and the stopping of the motor. 100

4. The combination with winding mechanism for insulated wire, of a motor and motor-controlling means, an electro-magnetic switch associated with the motor-controlling means, a fixed conducting member and a pivoted conducting member, a spring tending to move said members into engagement with each other, said members being held apart and insulated from each other by the insulated wire, and a circuit-closer operated by the pivoted member when an enlarged portion passes between said members, circuits and connections to effect the opening of said electro-magnetic switch and the stopping of the motor when said members are electrically connected by bare wire or by the operation of said circuit-closer, and 115

means for holding said switch in open position.

5. In a winding machine, the combination with winding mechanism and a motor, of a guiding arm pivoted for horizontal movement, means whereby the arm may be lifted vertically, and a dashpot connected to said arm for retarding the movement in a horizontal direction.
- 10 6. In spool winding machines, the combination with winding mechanism and a motor, of a horizontally and vertically pivoted guiding arm, a handle for moving said arm vertically, a resilient device for press-

ing the arm downwardly, an additional 15 handle for moving the arm laterally on its horizontal pivot, a dashpot for retarding such lateral movement, and means for regulating said dash-pot to secure an automatic lateral movement of the arm as the material 20 is being wound.

In testimony whereof, I have signed my name to this specification in the presence of two subscribing witnesses.

CAMPBELL SCOTT.
